UNITED STATES PATENT OFFICE.

CHARLES HABART, OF CLEVELAND, OHIO.

METHOD OF MAKING HINGES.

Application filed November 26, 1924. Serial No. 752,311.

The present invention relates to spring hinges and their method of manufacture, and more particularly to spring hinges of the type in which the spring element is adapted to be retained by one of the leaves of the hinge when the leaves are disconnected by the removal of the hinge pintle. This application is a continuation in part of my co-pending application, Serial No. 600,615, filed November 13, 1922.

By the present invention I have provided a hinge having a barrel portion forming an integral part of one of the leaves and constituting a housing for the spring element which is securely retained thereby under an initial tension. The hinge consists of but four parts, namely, the two leaves, the spring element, and the hinge pintle. The blanks for the two leaves are adapted to be stamped and punched from sheet metal at a single operation. In the illustrated embodiment of the invention the spring element consists of two coil springs placed end to end, but a single coil spring may be employed if desired.

In stamping out the blank for the leaf, which is to have the integral spring-retaining barrel portion, the tongue, which is later bent to form said barrel portion, is provided with a central longitudinally extending slot to receive the adjacent end portions of the springs and is also provided at its free end with slots or notches to receive the remote end portions of the springs. In assembling the springs with the leaf, the barrel forming tongue and the ears which form the end closures for the barrel portion are bent up at approximately right angles to the body of the blank. The springs are then placed between the bent up ears with their adjacent end portions projecting through the central slot in the tongue. The tongue is then bent into barrel form about the springs. This operation serves to place the springs under an initial tension, as will be hereinafter apparent. The cooperating leaf is formed from the stamped and punched blank by simply bending up the pintle-receiving ears at right angles to the body of the blank.

The hereinbefore described method of manufacturing my improved hinge will be more apparent by reference to the accompanying drawings, wherein:

Figures 1 and 2 are plan views of the stamped and punched blanks from which the two leaves of the hinge are formed;

Figure 3 is a plan view of the leaf formed from the blank shown in Figure 1;

Figure 4 is a plan view of the blank shown in Figure 2 with the ears and tongue bent up to receive the springs;

Figure 5 is an end view of the blank shown in Figure 4, showing the springs in position and the bending tool in engagement with the tongue;

Figure 6 is an end view corresponding to Figure 5 and showing the tongue bent around the springs to form the spring-retaining barrel portion;

Figure 7 is a plan view of the assembled hinge, and

Figure 8 is a section on the line VIII—VIII of Figure 7.

In constructing a hinge according to the present invention, the blanks 2 and 3, shown in Figures 1 and 2, for the leaves are stamped and punched from sheet metal. The blank 2 is provided with ears 4 having pintle-receiving openings 5 and the body of the blank has the usual holes 6 for the screws whereby the leaf is attached to a door or door frame. In order to form the leaf from this stamped and punched blank it is only necessary to bend up the two ears 4 on the dot and dash lines 7 until they stand at right angles to the body of the blank, as illustrated in Figure 3.

The blank 3 has an integral tongue 8 provided with a central longitudinally extending slot 9 and with relatively short slots or notches 10 at the free end of the tongue formed by cutting away the metal at the opposite corners of the tongue. The tongue has integral ears 11 projecting from the opposite side edges thereof adjacent the body of the blank. These ears have pintle-receiving holes 12, while the body of the blank has the usual holes 13 for the attaching screws.

In order to adapt the blank shown in Figure 2 to receive the coil springs 14, the tongue 8 and the ears 11 are bent up, by any suitable means, so as to extend at substantially right angles to the body of the blank. The blank is then in the condition shown in Figure 4. The coil springs 14 are then placed between the bent up ears 11 with their adjacent end portions 15 projecting through the slot 9 in the tongue 8, and with the remote end portion 16 engaging the body of the blank. A suitable bending tool 17 is then

placed in engagement with the free end of the tongue, as illustrated in Figure 5, and as this bending tool descends the tongue is bent into barrel form, shown in Figure 6, 5 with its free end engaging or substantially engaging the body of the blank, and with the end portion 16 of the springs projecting through the slots or notches 10 in said free end of the tongue.

10 It will be noted by comparing Figures 5 and 6 that the coil springs 14, when placed between the bent up ears 11, project above the upper edges of said ears. When the tongue is bent around these coil springs they 15 are forced down between the ears, thus increasing the angle between the projecting end portions 15 and 16 of the springs and placing the springs under an initial tension.

18 It will be noted by reference to Figure 4 that when the tongue 8 and ears 11 are bent up at right angles to the body of the blank the outer surfaces of the ears 11 are substantially flush with the longitudinal edges of the tongue, so that when the tongue is bent 23 into the barrel form shown in Figure 6 the tongue is bent into engagement with the peripheral edges of the ears, the latter forming end closures for the barrel portion of the leaf.

20 The distance between the inner surfaces of the bent up ears 4 of the leaf 2 is slightly greater than the length of the barrel portion of the leaf 3 so that in assembling the leaves, as shown in Figure 7, the barrel portion fits 25 between the ears 4 and the openings 5 in the ears 4 align with the openings 12 in the ears 11. The two leaves are connected by inserting a removable pintle 18 through these registering openings.

30 When the two leaves are connected, the end portions 15, which project through the slot 9 in the barrel portion of the leaf 3, are adapted to bear upon the leaf 2. Since the end portions 15 and 16 normally extend 35 at an angle to each other slightly less than 180°, the connected leaves tend to assume the relative positions shown in Figure 8, that is, with the body portions of the leaves extending at an angle to each other corresponding 40 to the normal angle between the end portions 15 and 16 of the springs. When the leaves are attached to a door and door frame the body portions of the leaves extend in the same plane, whereby the projecting end portions 45 15 are held out of engagement with the lower edge of the slot 9. This puts an increased tension on the springs and this tension is exerted on the leaves and is sufficient to hold the door in closed position with considerable pressure against the door frame.

50 In using a pair of these hinges to secure a door to its frame, the leaves carrying the springs can be attached either to the door or to the frame, preferably to the door.

55 When it is desired to take the door down all

that is necessary is to remove the pintles and the springs will be retained by the leaves having the barrel portions formed thereon.

It will be apparent that the present invention provides a hinge of simple construction which can be cheaply manufactured from sheet material by stamping and punching the blanks for the leaves and then bending them to form as described. The springs are securely held in the spring-retaining barrel and there is no possibility of the springs becoming displaced or lost when the leaves are disconnected by removing the hinge pintle.

While I have illustrated and described a preferred embodiment of my invention, it will be understood that the invention may be otherwise embodied within the scope of the appended claims without departing from the spirit of the invention.

I claim:

1. In the method of manufacturing spring hinges, the steps consisting in forming from sheet metal a blank for a leaf having an integral slotted tongue portion projecting from the body portion of the blank, placing a coil spring on said blank with one end portion thereof projecting through the slot in said tongue and the other end portion thereof engaging said body portion, and bending said tongue around said spring to form a retaining housing therefor, substantially as described.

2. In the method of manufacturing spring hinges, the steps consisting in forming from sheet metal a blank for a leaf having an integral slotted tongue portion projecting from the body portion of the blank, placing on said blank a coil spring having its end portions projecting at an angle to each other with one of said end portions projecting through the slot in said tongue and the other end portion engaging said body portion, and bending said tongue around said spring to form a retaining housing therefor and compress said spring to increase the angle between said projecting end portions thereof and thereby place the spring under an initial tension, substantially as described.

3. In the method of manufacturing spring hinges, the steps consisting in forming from sheet metal a blank for a leaf having an integral slotted tongue portion projecting from the body portion of the blank, bending said tongue to extend at an angle to said body portion, placing on said blank a coil spring having its end portions projecting at an angle to each other with one of said end portions projecting through the slot in said tongue and the other end portion engaging said body portion, and bending said tongue around said spring to form a retaining housing therefor and compress said spring to increase the angle between said projecting end portions thereof and thereby place the

spring under an initial tension, substantially as described.

4. In the method of manufacturing spring hinges, the steps consisting in forming from sheet metal a blank for a leaf having an integral slotted tongue portion projecting from the body portion of the blank, and having integral ears projecting from the opposite side edges of said tongue, bending said ears to extend at right angles to said body portion, placing a coil spring on said blank between said ears with one end portion thereof projecting through the slot in said tongue and the other end portion engaging said body portion, and bending said tongue around said spring to form with said ears a retaining housing for said spring, substantially as described.

5. In the method of manufacturing spring hinges, the steps consisting in forming from sheet metal a blank for a leaf having an integral slotted tongue portion projecting from the body portion of the blank and integral ears projecting from the opposite side edges of said tongue and provided with pintle-receiving openings, bending said ears to extend at substantially right angles to said body portion, bending said tongue to extend at an angle to said body portion, placing on said blank a coil spring having its end portions projecting at an angle to each other with one of said end portions projecting through the slot in said tongue and the other end portion engaging said body portion, and bending said tongue around said spring to form with said ears a retaining housing therefor and compress said spring to increase the angle between said projecting end portions thereof and thereby place the spring under an initial tension, substantially as described.

6. In the method of manufacturing spring hinges, the steps consisting in forming from sheet metal a blank for a leaf having an integral slotted tongue portion projecting from the body portion of the blank and

integral ears projecting from the opposite side edges of said tongue and provided with pintle-receiving openings, bending said ears to extend at substantially right angles to 50 said body portion, placing a coil spring on said blank with one end portion thereof projecting through the slot in said tongue and the other end portion engaging said body portion, bending said tongue around said 55 spring to form with said ears a retaining housing therefor, forming from sheet metal a blank for a cooperating leaf having integral ears for cooperation with the ears of the first blank and provided with pintle-receiving 60 openings, and bending said ears to extend at right angles to the body portion of the blank, substantially as described.

7. A method of forming a spring-retaining spring-hinge section, which consists in 65 forming from sheet metal a blank having a flat spring-embracing tongue and having transversely extending ears, then curling the tongue about a coil spring having an extension thereon and causing the curled portion to simultaneously distort the spring to put it under compression, and then folding the transverse ears perpendicular to the blank. 70

8. A method of forming a spring-retaining spring-hinge section, which consists in forming a blank from a sheet of metal having a tongue and having ears which are transverse to the tongue, curling the tongue about a coil spring having a laterally projecting end portion with the end portion at the edge of the curled tongue, folding the transverse ears perpendicular to the blank and thereby confining the end portion of the spring between one edge of the curled tongue 85 and one of the said ears, and placing the spring under compression and confining it against release by the said curling and folding operations.

In testimony whereof I have hereunto set 90 my hand.

CHARLES HABART.
